SHEET MUSIC STORAGE RACK

Pamela E. Burke, Boise, Idaho
(1153 Norton, Idaho Falls, Idaho 83401)

Filed Nov. 5, 1969, Ser. No. 19,946

Term of patent 14 years

Int. Cl. D6—01

U.S. Cl. D33—3

FIG. 1

FIG. 1 is a right front perspective view of the sheet music storage rack embodying my new design;

FIG. 2 is a left rear perspective view.

I claim:

The ornamental design for a sheet music storage rack, substantially as shown.
